INSULATING IMPLEMENT FOR USE IN A MICROWAVE OVEN

Filed Oct. 26, 1966

2 Sheets-Sheet 2

would be lost emanating from load 7 by radiating through the material or vacuum in cavity 4 is not lost as it is reflected back to load 7 by wall 9 of cavity 4 being heat reflective. Hence, the insulating implement A is useful to minimize heat loss by load 7 during the emission of microwave energy.

Said another way, similar mating implements, one insulating implement A and one heating implement B, can be combined, stacked and used in many useful groupings. FIG. 4 shows a representative sample of such groupings. The examples shown schematically in FIG. 4 are as follows:

- (a) Insulating dish A holding load C;
- (b) Insulating dish A hold a heating dish B holding a load C;
- (c) Insulating dish A holding a load C which is heated from the top by heating dish B';
- (d) Load C confined between two insulating dishes A and A';
- (e) Insulating dish A holding a heating dish B holding a load C covered by insulating dish A';
- (f) Insulating dish A holding load C. Load C covered and heated by heating dish B' whose heat is directed and confined by insulating dish A'; and
- (g) The insulating action or the heating action can be multiplied by using multiple implements—two insulating dishes A and A holding two heating dishes B and B holding load C.

FIGS. 5 and 6 illustrate another embodiment of this invention having utility as a removable, cleanable bottom tray for a microwave oven. This insulating tray besides its insulating properties (which keeps the heat generated in the load from being lost through the bottom metallic surface of the oven) positions the load high enough from the bottom surface of the oven to subject the load to the active microwave field. Illustrated are integral supporting structures 18 for providing additional strength when a vacuum is employed. This tray can be made of two separate pieces and fastened together by member 12.

My insulating implement in the configuration of a shelf for a microwave oven will conserve the amount of power needed to heat a load, versus a normal shelf which acts as a fin to dissipate heat.

My insulating implement could also be made in the configuration of a wall (FIGS. 5 and 6) or a brick (not shown) to improve the construction of my microwave kiln described in my aforementioned copending application, Ser. No. 497,851. These novel microwave oven walls and bricks may be used alone or in conjunction with other conventional insulating material.

As seen in FIG. 7, similar heating and insulating dishes as described may be constructed from halves of two complementary molds. FIG. 7 and FIG. 8 illustrates two mating halves 13 and 14 which together make one dish. The dish rims 15-15 are sealed at 20 (FIG. 8) to form a cavity 4' within the dish. If sealed at high temperature rarefied dry air would be trapped in this cavity 4' to ultimately become the insulating element in the insulating dish A. The heating dish B would be constructed by filling the cavity with a suitable lossy material and the two halves sealed at rim 15. The cavity 4' need not cover the whole inside area of the dish or be centrally or symmetrically placed, but may be selectively placed to enhance some cooking function. So, in cooking two unequally heating loads on one plate, a slower heating load, not shown, may be placed on the insulating portion of the dish and a faster heating load, not shown, on the regular portion of the dish to achieve planned even heating. A heat directing and equalizing shield 16 can be located in cavity 4' on option. This shield 16 could be made of radiant heat reflecting material.

A glass-ceramic which can withstand extreme temperature shocks is recommended for an insulating dish used in conjunction with my heating dish because of the 75

practice of precharging a heating dish with heat prior to using it to sear frozen meat.

With the foregoing and other objects in view, the invention resides in the novel arrangement and combination of parts and in the details of construction here described and claimed, it being understood that changes in the precise embodiment of the invention here disclosed may be made within the scope of what is claimed without departing from the spirit of the invention.

I claim:

1. An insulating and heating implement for use with apparatus employing electromagnetic wave irradiation in the microwave region, which comprises:
  - a first body having a cavity therein which is formed by a plurality of heat reflective surfaces,
  - a second body in contact with said first body and having a cavity therein, said second body capable of holding a workload,
  - a plurality of resistive particles located within said second body cavity, which when exposed to microwave irradiation, results in a multitude of arcs being generated therethrough so as to convert microwave energy into heat energy, and
  - a third body having a cavity therein which is formed by a plurality of heat reflective surfaces, said first, second and third bodies being constructed of microwave permeable material, said third body being so disposed with said first body that the surfaces are capable of reflecting the generated heat energy towards and away from each other, thereby permitting a maximum amount of heat energy to remain within the implement to heat the workload.
2. An insulating and heating implement according to claim 1 wherein the first body cavity is evacuated.
3. An insulating and heating implement according to claim 1 wherein the third body cavity is evacuated.
4. An insulating and heating implement according to claim 1 wherein said first body cavity is provided with a heat insulating material.
5. An insulating and heating implement according to claim 1 wherein said first body cavity is provided with a heat insulating material.
6. In a microwave oven comprising a chamber for receiving a workload and means for emitting microwave energy to said workload, for use in said oven, an improved, heat-insulating implement, in the form of an oven wall, for confining heat generated from said microwave energy, said improved, heat-insulating implement comprising in combination:
  - a body constructed of a material for permitting the passage of microwave energy therethrough, said body having a cavity therein formed by a plurality of surfaces wherein at least one of said surfaces is relatively more heat reflective than heat absorptive for impeding radiant heat loss, and
  - a microwave permeable heat insulator disposed within said cavity for impeding the passage of conductive and convective heat flowing through said cavity.
7. In a microwave oven, according to claim 6, wherein the cavity is evacuated.
8. In a microwave oven comprising a chamber for receiving a workload and means for emitting microwave energy to said workload, for use in said oven, an improved, heat-insulating implement, in the form of an oven shelf, for confining heat generated from said microwave energy, said improved, heat-insulating implement comprising in combination:
  - a body constructed of a material for permitting the passage of microwave energy therethrough, said body having a cavity therein formed by a plurality of surfaces wherein at least one of said surfaces is relatively more heat reflective than heat absorptive for impeding radiant heat loss, and
  - a microwave permeable heat insulator disposed within

said cavity for impeding the passage of conductive and convective heat flowing through said cavity.

9. In a microwave oven, according to claim 8, where-
in the cavity is evacuated.

10. In a microwave oven comprising a chamber for receiving a workload and means for emitting microwave energy to said workload, for use in said oven, an improved, heat-insulating implement, in the form of a utensil for holding said workload, for confining heat generated from said microwave energy, said improved, heat-insulating implement comprising in combination:

a body constructed of a material for permitting the passage of microwave energy therethrough, said body having a cavity therein formed by a plurality of surfaces wherein at least one of said surfaces is relatively more heat reflective than heat absorptive for impeding radiant heat loss, and
a microwave permeable heat insulator disposed within said cavity for impeding the passage of conductive and convective heat flowing through said cavity.

11. In a microwave oven, according to claim 10, where-
in the cavity is evacuated.

12. In a microwave oven comprising a chamber for receiving a workload and means for emitting microwave energy to said workload, for use in said oven, an improved, heat-insulating implement, in the form of a tray, for confining heat generated from said microwave energy, said improved, heat-insulating implement comprising in combination:

a body constructed of a material for permitting the passage of microwave energy therethrough, said body having a cavity therein formed by a plurality of surfaces wherein at least one of said surfaces is relatively more heat reflective than heat absorptive for impeding radiant heat loss, and

a microwave permeable heat insulator disposed within said cavity for impeding the passage of conductive and convective heat flowing through said cavity.

13. In a microwave oven, according to claim 12, where-
in the cavity is evacuated.
